ULTRA HIGH FREQUENCY ANTENNA
STRUCTURE

William W. Hansen, Garden City, N. Y., assignor
to The Sperry Corporation, a corporation of
Delaware

Original application January 16, 1942, Serial No.
426,986, now Patent No. 2,468,751, dated May
3, 1949. Divided and this application May 1,
1943, Serial No. 485,554

16 Claims. (Cl. 343—100)

1

This invention relates to directional antennas and particularly to ultra-high-frequency antenna systems adapted to produce overlapping, highly directional spatial patterns.

The present application is a division of co-pending application Serial No. 426,986, filed January 16, 1942, now Patent 2,468,751, issued May 3, 1949.

An object of the present invention is to provide an antenna system adapted to produce alternate 10 and overlapping directional spatial patterns.

Other objects and advantages will become apparent from the specification, taken in connection with the accompanying drawings wherein the invention is embodied in concrete form.

In the drawings, Fig. 1 is an oblique view of an antenna system comprising one directional wave guide radiator and two directional wave guide receptors as employed in the present invention.

Fig. 2 is an oblique view, partially broken away, of a portion of one of the wave guide receptors shown in Fig. 1.

Fig. 3 is an idealized elevation view of the shifting fan-shaped directional pattern employed in the present invention.

Fig. 3A is an idealized sectional view of the directional pattern shown in Fig. 3.

Fig. 4 illustrates an impedance matching transformer and commutator.

Figs. 5 and 6 show parts of Fig. 4 in detail.

Figs. 7 and 8 are sketches illustrating the operation of Fig. 4.

In parent application Serial No. 426,986 there is disclosed a system for the location of objects by using a highly directional radiation pattern and overlapping, alternate, highly directional receptivity patterns. Also disclosed is a system using overlapping, alternate, highly directional radiation and receptivity patterns. The present divisional application relates to the novel antenna apparatus disclosed in the parent application for producing such spatial patterns.

The parent application discloses an ultra-high-frequency signal generator suitable for supplying energy to one of the antennas disclosed herein and two ultra-high-frequency receivers for detecting the energy received by the other two antennas disclosed herein.

Referring now particularly to Fig. 1, rotatable pedestal 200 supports a yoke 201 which has a frame 202 swung between the arms of the yoke on trunnions. The right trunnion 203 passes through the yoke arm and forms the shaft of a gear 204 which is engaged to the driving pinion 206 of a motor 207. On the frame 202 are mounted wave guide radiator 208 and two wave guide receptors 209 and 210. Wave guides 208 and 209 are positioned parallel to one another, 60

2

and wave guide 210 is positioned at right angles to wave guides 208 and 209.

The radiator 208 contains a probe located at the junction between each branch of the wave guide, and, when excited by an ultra-high-frequency signal, the radiator serves to produce a symmetrical, fan-shaped beam of electromagnetic energy which is highly directional in the plane determined by the axes of the two wave guides and broadly directional in a plane at right angles to this plane.

Receptors 209 and 210 contain within each receptor two probes positioned as explained below, so that the receptivity gain characteristic for each receptor comprises two unsymmetrical, fan-shaped, overlapping patterns.

The wave guides employed in this antenna system are more fully discussed in copending application Serial No. 344,633 filed on July 10, 1940, now Patent No. 2,489,288 granted on November 29, 1949, in Patent No. 2,402,622 granted on June 25, 1946, and in Patent No. 2,432,990 granted on December 23, 1947, each of these references being in the name of the present inventor. The wave guides are constructed with two branches disposed at an angle with respect to each other of rectangular cross-section and of a length great compared to the other dimensions. The guides have narrow longitudinal slots on the opposed faces of the branches. Electromagnetic waves may be propagated from a radiator placed at the common junction or apex of the branches outwardly along their length at a phase velocity dependent on the cross-sectional area for a given frequency. The radiation escapes through the slots and substantially none reaches the ends of the guides which may be left open. The direction of propagation of the radiated waves in free space forms an angle with their direction in the hollow wave guide whose cosine is the ratio of the phase velocity of the waves in free space to that of the phase velocity of the waves in said guide. Thus, at a particular frequency the two branches of a guide may be angularly adjusted to have a common direction of propagation of free space radiation along the bisector of the angle between the branches. Under these conditions there is obtained the fan-shaped beam desired for radiator 208.

Fig. 2 shows a possible arrangement inside wave guides 209 and 210. Probes 215 and 216 are mounted in wave guide branches 217 and 218, respectively, equi-distant from the common junction or origin of the guide. Slots 219 and 220 enable the probes to be adjusted to a distance, preferably, one-eighth wave length from the origin. In operation, probes 215 and 216 in each of the receptors 209 and 210 are alternately activated and connected to detecting means through concentric lines 126 and 127 at a pre-

determined rate by a pair of suitable high frequency commutator switches.

When probes 215 and 216 of each of the receptors 209 and 210 are positioned one-eighth wavelength from the bisector of the angle between the branches of the wave guide, the gain characteristic of the receptor associated with each probe is an unsymmetrical fan-shaped pattern whose axis of maximum gain is shifted slightly from the bisector of the angle formed by the branches of the wave guides. The change in gain is more abrupt on the side of the spatial pattern adjacent to the bisector and less abrupt on the far side than in the case of an antenna placed at the bisector of the angle formed by the branches of the wave guides.

Figs. 3 and 3A indicate the overlapping spatial patterns representing the gain characteristic of the receptor indicated in Fig. 2. Each of these patterns is highly directional in the plane determined by the axes of the two wave guides and broadly directional at right angles to this plane. The axes of maximum gain of the spatial lobes are equi-angularly displaced to each side of azimuth axis 300 of the locating system so that the gain characteristics of the receptors associated with probes 215 and 216 are equal along azimuth axis 300. Principal lobe 160, having an axis of maximum gain 301, represents the gain characteristic of the receptor associated with probe 215, for example, and lobe 161, having an axis of maximum gain 302, represents the gain characteristic of the receptor associated with probe 216.

In operation, if a target is within the combined receptivity patterns of the two receptors but is not within the pattern formed by the central axis of each pair of overlapping patterns, it reflects more energy to one of the probes than to the companion probe, and the amplitude of the signals in the detector will be greater when the former probe is connected by the switching device than when the latter is connected.

Figs. 4 to 8 disclose a commutator suitable for use with the antenna system disclosed herein. Parent application Serial No. 426,986 discloses the same commutator, and copending application Serial No. 664,764 filed on April 25, 1946, which is a division of the present application, discloses and claims this commutator.

Referring now to Fig. 4, there is shown the commutator disclosed in the copending application cited above. Concentric line 126 from probe 215 connects to a line 122 through the horizontal branches of a cross-shaped adjustable coupling 124, illustrated in Fig. 5 in greater detail. In a similar way concentric line 127 from probe 216 connects to a line 123 through the horizontal branches of a cross-shaped adjustable coupling 125. Lines 122 and 123 join to form the coaxial cable 17 which connects the antenna system to detecting means. Vertical stubs of the couplings 124 and 125, projecting above the junction with the horizontal branches, contain adjustable shorting plugs 128 and 129, respectively. Vertical sections extending below the crossing adjustably attach to lines 131 and 132, which latter issue from shielding boxes 133 and 134, respectively. Shafts 141 and 142, having attached pinions 137 and 138, respectively, project from the shielding boxes 133 and 134. Gears 139 and 140 on a shaft 136 mesh with pinions 137 and 138, respectively. A gear 143 on the shaft 144 of the motor 15 engages the gear 140, and consequently the shafts 141 and 142 through their associated gearing are 75

rotated synchronously with the motor 15. Coupling 124, line 131, box 133, shaft 141, and gear 137 are designed to be horizontally displaceable as a unit within a wavelength of the operating carrier frequency, for tuning purposes, as is the combination of coupling 125, line 132, box 134, shaft 142 and gear 138. The pinions 137 and 138 have lengths adequate to allow for these displacements. The distance between the centers of devices 124 and 125 and the shielding boxes 133 and 134, respectively, may also be vertically adjusted by means of the slideable attachment between the lower arm of the devices 133 and 134 and coaxial lines 131 and 132, respectively.

Fig. 5 is a detailed sectional view of the left portion of Fig. 4 revealing the method of joining the coaxial lines and the interior arrangement of shielding box 133. The inner conductors 122', 126' and 131' of the coaxial lines 122, 126 and 131, respectively, are hollow and of such an interior diameter as to permit the inner conductors 124' of the device 124 to slide therein. The exteriors of lines 122, 126 and 131 are likewise enlarged to allow the exterior of the device 124 to slide therein. Insulating washers 146 and 147 support the inner conductors 124' coaxial with the exterior of device 124. An insulating washer 148 supports the inner conductor 131'. The ratio of the outside diameter of conductors 124' to the inside diameter of the exterior conductor of device 124 is made substantially equal to the ratio of the outside diameter of conductors 122', 126' and 131' to the inside diameter of their respective exterior conductors to maintain the characteristic impedances of the various sections equal. The shorting plug 128 is made with a hollow shaft to facilitate the longitudinal adjustment within the upright stub of device 124. The conductor 131' projects into the shielding box 133 where a condenser plate 149 is soldered to its end. The plan view of a preferred form of the plate 149 is shown in Figs. 7 and 8. The other plate of the condenser may be considered the adjacent side of the shielding box 133. The coaxial line 131 and the section of device 124 below the junction, therefore, is terminated by a capacitance whose magnitude depends on the area of the plate 149 and the spacing and dielectric constant between the plate and the side of the box 133. The shaft 141, driven by the motor 15 through the gears 137, 139, shaft 136, gears 140, 143 and shaft 144, as mentioned above, rotates in ball-bearings 151 and spins a double-bladed chopper 152 between the plate 149 and side of the box 133. Device 152 is roughly similar to a light chopper used in motion picture art. Fig. 5 moves one of the blades of the chopper 152 meshed as in Fig. 8. Fig. 6 is an alternate view of the box 133 taken at right angles to the plane of Fig. 5 looking from the base of the box at the end of the conductor 131'.

The chopper 152 may be constructed of a high dielectric constant, low loss non-conductor or may be made of a conductor which is insulated from the shaft 141. The effect of a non-conductor is to increase the capacity when meshed with plate 149 because the dielectric constant of the intervening space is increased. The effect of an insulated conductor is to create two condensers in series which have increased capacity due to the reduced air gaps, and the capacity of the series combination is greater than the capacity in the open position. The shielding box 133 is dimensioned to be non-resonant to the transmitter frequency.

The operational alignment of commutator 16 as shown in Fig. 4 is simplified by utilizing the teaching of the Reciprocity Theorem which allows the substitution of an ultra-high-frequency oscillator in place of the detector on the end of the coaxial line 17 to provide a temporary local power source. The alignment, which is undisturbed by this substitution, may be performed by the following steps:

First, mesh the left-hand chopper 152 as shown in Fig. 8 and adjust the length of the line from the plate 149 to the center of the coupling 124 until no energy flows down the left line 126 to probe 215. This means there is an effective short at the center of the coupling 124.

Repeat this adjustment for the right-hand side of the apparatus shown in Fig. 4.

Next, unmash the left-hand chopper 152 as shown in Fig. 7 and adjust the plug 128 in the stub of the coupling 124 until there are no standing waves in the line 122. This means there is no reflection from the center of the coupling 124 and energy may flow unimpeded to the left probe 215.

Repeat this adjustment for the plug 129.

Then, with chopper 152 meshed and the corresponding chopper in box 134 unmashed, adjust the combined lengths of the right branch of coupling 124 and line 122, until there are no standing waves in the "oscillator" line 17. This means that when the center of coupling 124 is effectively shorted the "oscillator" end of the line 122 is made to appear as an open circuit and there is no loss of power due to the short at the center of coupling 124.

Repeat this adjustment for the right side of the apparatus shown in Fig. 4.

Adjust the length of coaxial line 126 to the probe 215 with the chopper 152 meshed until the line has no field present indicating that the inactive probe 215 is absorbing no energy from the active probe 216. This means that when the center of coupling 124 is effectively shorted, the antenna end of the line 126 is made to appear as an open circuit, and there is no loss of radiated power from the energized probe 216.

Repeat this adjustment for the right-hand line 127.

These above steps are repeated until the alignment conditions are satisfied. The purpose of the stub line on coupling 124 is to couple a conjugate impedance to the center of coupling 124 which will compensate for the fact that the chopper 152 produces only a finite change of capacity.

The parent application discloses a system adapted to continuously orient an antenna system of the type disclosed herein so that the fan-shaped overlapping patterns of each receptor are caused to continuously enclose the object to be located within the region defined by the central axis of each pair of overlapping patterns.

It will be apparent to one skilled in the art that the directional characteristics of the wave guide and probes indicated in Fig. 2, employed as receptors, apply equally to the wave guide and probes employed as radiators.

The parent application also discloses a system in which an antenna structure as indicated in Fig. 1 may be utilized employing two probes as shown in Fig. 2 in the radiator and in one of the receptors and employing a single probe placed at the junction between each branch of the wave guide in the other receptor.

As many changes could be made in the above construction and many apparently widely dif-

ferent embodiments of this invention could be made without departing from the scope thereof, it is intended that all matter contained in the above description or shown in the accompanying drawings shall be interpreted as illustrative and not in a limiting sense.

What is claimed is:

1. High-frequency apparatus comprising means for generating electromagnetic energy, transducing means mounted within a pair of hollow inclined waveguides, a transmission line connecting said generating means to said transducing means, impedance matching and commutating means employed in the line connection between said generating and transducing means, said communicating means comprising variable impedance means effectively varying the line impedance.

2. A high frequency apparatus comprising means for generating electromagnetic energy, transducing means mounted within a pair of waveguides, said waveguides forming a predetermined angle with respect to each other and having means for electromagnetically coupling said guides to surrounding space, a transmission line connecting said generating means to said transducing means, impedance matching and commutating means comprising variable impedance means connected between said generating and transducing means, said commutating means comprising variable impedance means effectively varying the line impedance.

3. High frequency apparatus comprising means for producing partially overlapping fan-shaped radiation patterns comprising two hollow conducting radiating waveguides forming a predetermined inclined angle with respect to each other, means in each guide for alternately launching electromagnetic waves of substantially linear polarization for travelling along said guides, distributed means for radiating said waves extending along the length of said guides substantially at right angles to the electric vector of said waves, said launching means being spaced at a predetermined distance from the vertex of the angle formed by said hollow waveguides for introducing phase differences between the electromagnetic waves at corresponding points within said guides so that nonsymmetrical overlapping patterns are alternately produced.

4. High frequency apparatus for producing partially overlapping fan-shaped radiation patterns comprising two hollow conducting radiating wave guides forming a predetermined inclined angle with respect to each other, means in each guide for alternately launching electromagnetic waves of substantially linear polarization for traveling along said guides, and distributed means along the length of said guides for radiating said waves, said launching means being spaced at a predetermined distance from the vertex of said angle formed by said hollow wave guides and introducing phase difference between the electromagnetic waves at corresponding points within said guides so that unsymmetrical overlapping patterns are alternately produced.

5. High frequency antenna apparatus comprising a pair of slotted rectangular wave guides disposed at an angle to one another, and means for coupling to said wave guides, comprising a pair of concentric transmission lines, the inner conductors of said transmission line being disposed within respective ones of said wave guides

and symmetrically located with respect to the junction of said wave guides.

6. High frequency antenna apparatus, comprising a pair of interconnecting hollow wave guides disposed at an angle to one another, each having means distributed along the length thereof for electromagnetically coupling said waveguides to the space surrounding said waveguides, and alternate transducing means for exciting said wave guides with travelling waves, whereby said apparatus has a pair of partially overlapping, alternate directivity characteristics.

7. High frequency antenna apparatus comprising a pair of intercommunicating hollow waveguides disposed at an angle to one another, each having means distributed along the length thereof for electromagnetically coupling said waveguides to surrounding space, transducing means for launching travelling electromagnetic waves within said guides, said transducing means being mounted within said waveguides, and control means for intermittently introducing phase differences between electromagnetic waves at corresponding points within said guides to produce partially overlapping directivity characteristics in surrounding space.

8. A high frequency apparatus for projecting alternate fan-shaped beams, comprising hollow conducting waveguides having major axes materially longer than the transverse dimension of said waveguides, said waveguides further having openings extending along these major axes, means for producing in said waveguides phase differences between electromagnetic waves at corresponding points within said guides, and control means alternately exciting said last named means, thereby producing partially overlapping directivity characteristics in space.

9. A high frequency apparatus for projecting alternate fan-shaped beams, comprising a pair of hollow waveguide intercommunicating sections inclined at an angle of less than 180° with each other, transducing means mounted within said hollow waveguide portions, means for producing in said waveguide portions phase differences between electromagnetic waves at corresponding points within said waveguide portions, and commutating means cooperative with said transducing means to produce partially overlapping directivity characteristics in space.

10. High frequency apparatus comprising a hollow waveguide radiator, said radiator further comprising a pair of interconnected hollow waveguide portions disposed at an inclined angle to one another and having means distributed along the length thereof for electromagnetically coupling said waveguide portions to the space surrounding said portions, and plural means alternately exciting said waveguide portions with travelling waves, whereby said apparatus has a pair of partially overlapping alternate directivity characteristics.

11. High frequency radiating apparatus comprising a radiator having a pair of hollow waveguide portions disposed at an angle less than 180° with respect to one another and having a common vertex, said waveguide portions having slots in the faces opposing one another for permitting radiation of high frequency waves from within said waveguides, means for exciting said waveguides, comprising coupling means located within each of said waveguide portions at a distance from said vertex, and means for alter-

nately exciting said coupling means, whereby a pair of partially overlapping alternate directivity characteristics is produced.

12. High frequency radiant energy antenna apparatus comprising a radiator having a pair of hollow interconnected waveguide portions disposed at an angle with respect to one another to form a V, each of said waveguides having a slot in the wall thereof facing the other of said waveguide portions, coupling means mounted within each of said waveguide portions and displaced from the vertex of said V, and means for alternately exciting said coupling means, whereby said apparatus has a pair of partially overlapping alternate directivity characteristics.

13. High frequency antenna apparatus comprising a radiator having a pair of hollow waveguide sections disposed at an angle to form a V, each of said sections being apertured along the length thereof on the side facing the bisectrix of said V, and means for alternately exciting said waveguides with respective high frequency waves to produce partially overlapping alternate directivity characteristics in space.

14. High frequency antenna apparatus comprising a radiator having a pair of interconnected apertured hollow waveguides angularly disposed to form a V, and commutating means for alternately exciting said waveguides with respective high frequency waves having a relative phase difference, whereby a nonsymmetrical directivity pattern is produced.

15. High frequency antenna apparatus comprising a radiator having a pair of interconnected hollow waveguide sections angularly disposed with respect to one another, means for alternately exciting said waveguide sections to produce partially overlapping directivity characteristics in space, said last-named means comprising a high frequency coupling disposed within each of said waveguide sections.

16. High frequency apparatus comprising an antenna having a pair of hollow wave guides at an inclined angle to one another, said wave guides having means distributed along the lengths thereof for electromagnetically coupling said wave guides to the surrounding space, respective coupling means coupled to said guides for exchange of electromagnetic energy therewith, circuit means to be coupled to said antenna, and means alternately coupling said circuit means to said respective coupling means.

Certificate of Correction

Patent No. 2,500,178

March 14, 1950

WILLIAM W. HANSEN

It is hereby certified that errors appear in the printed specification of the above numbered patent requiring correction as follows:

Column 4, line 57, for the word "moves" read *shows*; column 6, lines 28 and 29, strike out "comprising variable imnected" and insert instead *employed in the line connected*;

and that the said Letters Patent should be read with these corrections therein that the same may conform to the record of the case in the Patent Office.

Signed and sealed this 27th day of June, A. D. 1950.
